FUEL FEEDING MECHANISM

Dwight M. Palm, Cleveland Heights, Ohio

Application November 27, 1943, Serial No. 512,076

3 Claims. (Cl. 214—36)

1

This invention relates to mechanism for supplying hard fuel to a combustion apparatus, more particularly apparatus of the type wherein the supply and feeding of the fuel into the combustion chamber of the apparatus takes place through upper and lower chambers having valve controlled openings, which valves are separately but co-ordinately controlled and operated to prevent the escape of gases and other residue of combustion into and through the supplying and feeding mechanism. The invention is, for illustrative purposes, shown as applied to a gas producer, to which the fuel is delivered in batches, at intervals, dependent on the rate of increase or decrease in fuel consumption, whereby the producer may be maintained adequately charged with fresh fuel.

One object of the invention is to provide an improved mechanism of this character wherein the number of parts are reduced and simplified in construction and fewer movable parts are required, whereby cost of construction, operation and up-keep is materially reduced and long life of the mechanism results.

Another object of the invention is to provide in mechanism of this type having upper and lower valves, improved means for operating the valves in any desired co-ordinated relation.

Another object of the invention is to provide in mechanism of this type having upper and lower valves, an improved operating means therefor which may be remotely controlled.

Another object of the invention is to provide in mechanism of this type having upper and lower valves, improved means for automatically controlling the operation of the valves dependent upon the rise and fall of the temperature in the apparatus.

Another object of the invention is to provide in mechanism of this type having upper and lower fuel feeding chambers and valves therefor, improved means for operating the valves in co-ordinated relation and supplying fuel to the upper chamber.

Another object of the invention is to provide an improved mechanism of this type having upper and lower valve controlled chambers and fluid operated means for operating the valves therefor in co-ordinated relation.

Another object of the invention is to provide an improved mechanism of this type constructed to provide for ready cooling of the valve which is subject to the heat generated in the combustion apparatus.

Other objects of the invention will be apparent

2

to those skilled in the art to which my invention relates from the following description taken in connection with the accompanying drawings, wherein

5 Fig. 1 is a front elevation of a mechanism embodying my invention.

Fig. 2 is a side elevation, parts being broken away.

Fig. 3 is a section on the line 3—3 of Fig. 1.

10 Fig. 4 is a fragmentary section through the valve.

Fig. 5 is a section on the line 5—5 of Fig. 4.

15 Figs. 5a and 6 are fragmentary elevations (parts being broken away) showing modified forms of construction.

In the drawings, 1 indicates as an entirety a casing of any desired shape in cross section, preferably substantially circular in shape, having on its lower end an annular flange 1a supported on 20 and secured to the annular flange on the upper end of a suitable gas producer, indicated at A, having a flue a for the out-take of the gases. The upper end of the casing is shaped to provide an off-set section 1b in connected relation to a 25 chute 1c, the intake opening of which is related to the discharge opening of a hopper B, which opening is controlled by a slide valve b. The walls of the off-set section 1b and a valve device 2 therewithin control the feed of the fuel C from the chute 1c, as later set forth. Above the flange 1a, the inner wall of the casing 1 is provided interiorly with spaced, annular, inwardly extending walls 3, the inner peripheries of which have a common axis and form seats 2a for valves 4, 4a. When the valves 4, 4a, are in closed position, they co-operate with the adjacent annular walls 3, to form upper and lower closed compartments 5, 5a, the upper compartment 5 being in communication with the off-set section 1b so as to receive fuel C therefrom; but when either valve is opened the fuel in the adjacent compartment gravitates downwardly. Accordingly, if the valve 4 is operated to open position, any fuel in the compartment 5 will gravitate into the compartment 5a and if the valve 4a is operated to open position any fuel in the compartment 5a will gravitate into the producer A. For obvious reasons the valves 4, 4a, move downwardly relative to their seats when opened; also their upper surfaces are dome-shaped and the upper surfaces of the annular walls 3 are inclined downwardly and inwardly, whereby gravitation of fuel from each compartment is facilitated. As shown each wall 3 is of sectional construction, so that its inner marginal portion may consist

of an annular ring 2a' formed of a heat resisting alloy, removably secured to the wall 3 in any suitable manner.

The side walls of the casing below the compartment 5a, between the compartments 5, 5a, and above the upper compartment 5 may be formed with one or more openings 5b, each closed by a plate which may be removably bolted in position or otherwise mounted on the casing wall.

The valves 4, 4a are supported in axial alignment and operated vertically, rectilineally, whereby their upper walls engage and disengage the valve seats uniformly throughout their circumferences, which arrangement prevents uneven wear on these seats on the one hand and on the other hand tends to insure tight closing of the valves so that leakage of gases of combustion and soot upwardly into the casing is minimized and danger of ingredients in the gases and soot clogging the mechanism is avoided.

The top wall 1d of the casing 1 is thickened to provide a relatively long hollow boss 1d' the axis of which is axially related to the axes of the walls 3. 6 indicates an elongated bushing suitably fitted in the boss 1d' and slidably supporting a sleeve 7, the latter extending downwardly through the compartment 5 and preferably rigidly connected at its lower end to the valve 4. 8 indicates a rod (which is preferably hollow for a purpose later set forth) slidably fitting the sleeve 7 and extending therethrough, and through the valve 4 and compartment 5a and preferably rigidly connected at its lower end to the valve 4a. In this arrangement, the valves 4, 4a, are positively guided from and to their seats in each operation thereof. The sleeve 7 and the rod 8 extend upwardly beyond the top wall 1d and are operatively connected to an operating mechanism, indicated as an entirety at 9, for intermittently reciprocating the sleeve 7 and rod 8 each relative to the other in co-ordinated relation, whereby during the period that the valve 4 is closed, the valve 4a opens to permit gravitation of the fuel in the compartment 5a into the producer A and closes, and during the period that the valve 4a is closed the valve 4 opens to permit gravitation of the fuel in the compartment 5 into the compartment 5a and closes; also, during the operation of the valve 4a to open and closed position (at which time the valve 4 is closed) the agitating or valve device 2 is operated, as later set forth, to supply fresh fuel to the compartment 5. The agitating device 2 is preferably operatively connected to the mechanism 9 for co-ordinated operation therewith during the opening and closing of the valve 4a, by mechanism indicated as an entirety at 10, to which reference will later be made.

The mechanism 9, as shown in Figs. 1 to 5, inclusive, is fluid operated; that is, it may be operated by air or oil supplied under pressure, but for illustrative purposes I use steam supplied as hereafter set forth by a pipe 11. The mechanism 9 consists of the following: 12 indicates a cylinder suitably supported at one side of and exteriorly of the casing 1. 12a indicates a rod reciprocatably mounted in the end walls of the cylinder 12 and extending to a point thereabove and therebelow and provided within the cylinder with a piston 12a' (see Fig. 2) normally disposed adjacent the lower end thereof. The lower end of the rod 12a has sliding support in a bracket 12'. The upper end of the rod 12a is connected through a linkage 13 to the upper end of the rod 8, the linkage preferably consisting of

a rocker fulcrumed on a standard 14 fixedly mounted on the top wall 1d. The rod 12a has pivotal and slidable connection with the outer end of the rocker 13 by means of a pin and an elongated slot 12b' therefor formed in the rocker, to permit endwise movement of the rod and swinging movement of the rocker; the connection between the upper end of the rod 8 and inner end of the rocker 13 is of similar character. The lower end of the cylinder 12 is provided with a port connected to a pipe 15 through which steam is supplied (preferably at a predetermined pressure, as later set forth) to the cylinder 12 below the piston 12a' and exhausted therefrom, the supply and exhaust being controlled by a valve mechanism, indicated as an entirety at 16. As will be observed, when steam is supplied to the cylinder to effect pressure on the piston, the rod 12a is operated upwardly and through the rocker 13 moves the rod 8 downwardly to open the valve 4a (see dotted lines in Fig. 3). The upper end of the cylinder 12 is provided with a vent 17 to permit displacement of air when the piston 12a' is operated upwardly. Below the cylinder 12, the rod 12a is provided with a collar 18, preferably formed integrally on the upper end of a sleeve 18a, which may be secured to the rod 12a in a manner which permits endwise adjustment thereof. The collar 18 forms an abutment for a spring 19 coiled around the rod 12a and interposed between the collar 18 and lower end of the cylinder 12 and arranged to be compressed when the rod 12a moves upwardly, so that when the steam supply to the cylinder 12 is cut off, and pressure on the piston 12a relieved, the spring 19 operates to move the rod 12a downwardly to close the valve 4a. A stop indicated at 12e is provided to limit the downward movement of the piston so that when the piston is moved downwardly to its normal position, it is above the steam inlet and exhaust port for the pipe 15. The stop 12e as shown consists of an annular shoulder provided in the cylinder by reducing its lower end (see Fig. 2). The sleeve 18a is preferably adjustably fixed to the rod 12a at a predetermined position so that when the valve 4a engages its seat the spring 19 is under slight tension, the effect of which is to seal the valve 4a in closed position. 12x indicates a cylinder suitably supported on and exteriorly of the casing 1, preferably in diametrical relation to the cylinder 12. 20 indicates a rod reciprocatably mounted in the end walls of the cylinder 12x and extending to a point thereabove and therebelow and provided within the cylinder 12x with a piston similar to the piston 12a' normally disposed adjacent the lower end thereof. The upper end of the rod 20 is connected through linkage 13x to the upper end of the sleeve 7, preferably consisting of a rocker fulcrumed on a standard 14x, which is fixedly supported on the top wall 1d.

The inner end of the rocker 13x is provided with bifurcations which are pivotally connected to bifurcations provided on the upper end of the sleeve 7, whereby these parts straddle the rocker 13 and rod 12a and the connections therebetween. The upper end of the rod 20 and adjacent end of the rocker are pivotally and slidably connected by means of a pin and an elongated slot 20a formed in the rocker and each bifurcation on the inner end of the rocker 13x is similarly connected to the adjacent bifurcation on the sleeve 7 to permit endwise movement of the rod and sleeve and swinging move-

ment of the rocker. The lower end of the cylinder 12x is provided with a port connected to a pipe 15a through which steam is supplied (preferably at a predetermined pressure, as later set forth) to the cylinder 12x below the piston therein and exhausted therefrom, the supply and exhaust being controlled by the valve mechanism 16. As will be observed, when steam is supplied to the cylinder 12x to effect pressure on the piston therein, the rod 20 is operated upwardly and through the rocker 13x moves the sleeve 7 downwardly to open the valve 4 (see dotted lines in Fig. 3). The upper end of the cylinder is provided with a vent 17x to permit displacement of air when the piston is operated upwardly. Below the cylinder 12x, the rod 20 is provided with a collar 18x, adjustably held in position thereon by a nut 18x'. The collar 18x forms an abutment for a spring 19x coiled around the rod 20 and interposed between the collar and the lower end of the cylinder 12x and arranged to be compressed when the rod 20 moves upwardly, so that when the steam supply to the cylinder 12x is cut off, and pressure on the piston relieved, the spring 19x operates to move the rod 20 downwardly to close the valve 4. A stop is provided in the cylinder to limit the downward movement of the piston, so that when the piston is in its normal position, it is above the steam inlet and exhaust port. The collar 18x is preferably adjustably fixed to the rod 20 in a predetermined position so that when the valve 4 engages its seat the spring 19x is under slight tension, the effect of which is to seal the valve 4 in closed position.

The agitating and feeding device 2 consists of a member fixed to a rock shaft 21 mounted in the side walls of the off-set 1b and arranged to be oscillated thereby. The agitating member 2 serves as a valve between the chute 1c and compartment 5 and extends across the off-set 1b, its upper side preferably being flat so that when in normal position it closes the lower end of the chute 1c (see Fig. 3) and serves as a support for the fuel therein, but when rocked to the position shown in dotted lines (Fig. 3) it provides between its inner end and the inner end wall of the off-set 1b an opening through which the fuel gravitates into the compartment 5. The outer end wall of the off-set is preferably curved on a radius struck from the axis of the rock shaft 21 and the outer end of the agitating member 2 is curved concentric to the outer end wall of the off-set 1b, so that no space in which the fuel can lodge, between these parts may exist or result due to oscillation of the device 2. The mechanism 10 for operating the agitating or valve member 2 consists of the following: 22 indicates a disk fixed to the rock shaft 21 exteriorly of and at one side of the off-set 1b. 22a indicates a flexible band frictionally engaging a portion of the periphery of the disk 22, the outer end of the band being connected to one end of an expansion spring 23, the opposite end of which is fixed to an adjustable anchor 23a mounted on the casing 1 (see Fig. 2). The opposite or inner end of the band 22a is connected through a link 24 to one arm 25 of a rocker 25' fulcrumed on the casing 1, the opposite arm 25a of the rocker 25' being disposed in the path of a collar 18' on the lower end of the sleeve 18a, so that when the rod 12a and sleeve move upwardly, the collar 18' will swing the rocker 25' counter-clockwise (as viewed in Fig. 2) and effect a pull on the inner end of the band 22a against the ten-

sion of the spring 23, whereby the disk 22 will be rotated and swing the valve member 2 to the position shown in dotted lines in Fig. 3. Upon the movement of the rod 12a downwardly, the spring 23 will rotate the disk 22 and swing the rocker 25' in the opposite direction. If in the return movement of the valve member 2, fuel becomes lodged between it and the inner end wall of the off-set 1b, the band 22a will slip on the disk without turning it. The outer end of the rocker arm 25a is preferably provided with a roller to reduce friction between it and the collar 18'. The rocker 25' is preferably provided with a laterally extending arm 25b carrying a roller at its outer end in position to be engaged by the inner end of a rod 26. The rod 26 is screw-threadedly mounted in an internally threaded member 27 fixedly supported on the casing 1, whereby the rod 26 may be adjusted endwise to swing the rocker about its fulcrum to relate the rocker arm 25a to the collar 18'. By adjusting the rod endwise inwardly, the rocker 25' will be rocked counter-clockwise (one adjusted position of the rocker being shown in dotted lines in Fig. 2) and position the outer end of the rocker arm 25a in spaced relation to the collar 18' when the latter is in normal position. Accordingly, when the rocker is adjusted as above set forth, the collar 18' will move a predetermined distance before engaging the rocker arm 25a and operating the rocker. By adjusting the rod 26, the movement of the rocker 25' and disk 22 can be regulated to decrease the quantity of fuel permitted to gravitate to the compartment 5 in each operation of the valve member 2.

The bottom annular wall 3 for the compartment 5a is preferably provided with an annular chamber 3x connected with valved inlet and outlet connections 3x', whereby water may be circulated through the chamber to maintain the wall 3 cool. Due to contact of the adjacent ring 2a' with the wall 3, a portion of the heat imparted to the ring 2a' will be conducted to the wall 3, so that the ring 2a' is maintained relatively cool. As will be observed the valve 4a is in position to be heated by the combustion taking place in the producer, but due to the mounting of the valves 4, 4a, I am able to provide for cooling the valve 4a in a simple manner. As shown, the valve 4a is hollow to provide therein a chamber 4a' into which the rod 8 (which is hollow as already set forth) extends. This construction permits the provision in the rod 8 of a small pipe 28 suitably connected to a nipple 28a at the upper end of the rod and extending into the chamber 4a' at its lower end, the nipple 28a being connected to a flexible hose 28a' leading from a source of water supply under pressure, the water supplied to the chamber 4a' being discharged therefrom through the pipe 8 around the pipe 28 and flowing out at the upper end of the rod 8 through a nipple 28b', which is connected by a flexible hose 28b' leading to a drain or sump.

The steam supply pipe 11 is provided with an adjustable pressure regulating valve 29, of any desired construction, arranged to be set at a predetermined pressure (preferably at 70 lbs. per square inch), whereby the pressure of the steam supplied to the valve mechanism 16 will at all times be uniform. The valve mechanism 16 is preferably of the rotary type, and driven through a suitable reduction gearing 30 by a motor 31, which is connected in a circuit 32 to mains 33.

In the herein disclosed application of my invention, the circuit 32 is provided with a switch

32' which is normally opened, so that the motor 31, the valve mechanism 16 and the operating mechanism 9 are normally at rest, but provision is made to automatically close and open the switch to start and stop the motor to effect operation of these mechanisms dependent on the heat of the gases flowing through the flue *a*. For this purpose I provide in the flue *a* an electro-thermo couple *a'* set to operate at a predetermined degree of temperature, so that when these gases rise in temperature, due to combustion in the producer A, to or above the predetermined degree, the switch 32' will be operated to close the circuit 32 and thus start the motor 31 in operation. The motor in turn operates the valve mechanism 16 whereby steam is supplied to the mechanism 9 to operate the valves 4, 4a, and feeder 2, in co-ordinated relation as already set forth, whereby fresh fuel (coal and the like) is delivered to the compartment 5, then to the compartment 5a and finally fed to the producer *a*. These operations will continue until the temperature of the gases in the flue *a* drops to a point below the predetermined temperature, whereby the electro-thermo couple *a'* will open the switch 32' and stop the motor.

The valve mechanism 16 comprises a casing 16a having conically shaped seats into which valve elements 16b, 16b', rotatably fit, the inner ends of the latter being connected together by an irregular shaped projection 16c fitting a complementary opening formed in the other element. The element 16b is removably connected to a fitting 16d held in position by a cap 16e which is threaded into the adjacent end of the casing 16a, a suitable bearing being provided between the fitting 16d and cap 16e and an expansion spring 16f is provided between the bearing and the adjacent valve element to retain the latter in its seat. The valve element 16b' is mounted similarly to the valve element 16b, except that the fitting 16d is connected (preferably integrally) to a shaft 16g, which is coupled to the shaft 33a of the reduction gearing 30 and driven thereby. The valve element 16b' is provided with a duct 16x, whereas the valve element 16b is provided with a duct 16x', these ducts being in diametrical relation. As shown in Fig. 1, the steam supply pipe 11 terminates in branches 11a, 11a', each connected to a port preferably formed in the upper wall of the valve casing 16a. The valve casing is provided (a) at one side with aligned ports, one thereof being connected to the pipe 15 and the other being connected to the pipe 15a and (b) at its bottom with aligned ports connected to exhaust pipes 15x, 15x', respectively, preferably leading to the air blast of the producer A. The duct 16x is so arranged that in one position of the valve element 16b' during rotation thereof it registers with the ports for the pipes 11a and 15 to supply steam to the cylinder 12 and in another position it registers with the ports for the pipes 15 and 15x to permit exhaust of the steam to and through the latter pipe, the ports for the pipes 11a, 15 and 15x being closed during the remaining rotary movement of the valve elements, whereas during the period the ports to the pipes 11a, 15 and 15x are closed, the duct 16x' in one position registers with the ports for the pipes 11a' and 15a to supply steam to the cylinder 12x and in another position with the ports for the pipes 15a and 15x' to permit exhaust of the steam to and through the latter pipe, the ports for the pipes 11a', 15a and 15x' being closed during the remaining rotary movement of the valve elements. As shown in Fig. 5, the valve elements 16b, 16b' ro-

tate clockwise, so that the steam is supplied to the cylinder 12x to effect operation of the valve 4 and exhausted therefrom prior to the supply of steam to the cylinder 12 and operation of the valve 4a, the speed of the valve elements being so regulated that during the period between the cut-off of the steam supply to each pipe 15, 15a, and its exhaust therethrough the valve 4 or 4a controlled thereby remains open long enough to permit gravitation of the fuel from the adjacent compartment.

Fig. 6 illustrates a modified form of construction wherein the sleeve 7 and hollow rod 8, which are connected to the valves 4, 4a, respectively, are connected to linkages 13x', 13x'', respectively, in the manner already set forth and the linkages in turn are operated and controlled by electrical means to coordinate the movements of the sleeve and rod in the manner already set forth. In this view, 34, 34a, indicate electric motors each connected by leads 35 to suitable contacts in a casing 36 having a rotary switch device therein driven by a motor 31, the device and motor being supplied with current from mains 38, the switch device serving to close one circuit and break the circuit and then to close the other circuit and break it, (a) the closing and opening of each circuit being effected during the period the other circuit is open and (b) each circuit being closed for a period long enough for the shaft of the adjacent motor 34, or 34a, to make one revolution, whereby the sleeve 7 and rod 8 are operated relative to each other in co-ordinated relation. The linkages 13x', 13x'', and their operating connection with the motors 34, 34a, respectively, are similar in construction and operation, so that one linkage and its connection with the adjacent motor will be referred to, that is, the linkage 13x' connected to the rod 8. This linkage comprises a rocker 39 fulcrumed on a standard 40 and connected at its inner end to the rod 8. The outer end of the rocker 39 is pivotally connected to the outer end of a sectional member 41, the inner end of which is pivotally connected to a crank 42 fixed to the shaft of the adjacent motor 34. The member 41 consists of an inner device 41a of tubular form having a reduced inner portion 41x pivotally connected at its outer end to the crank 42 and an enlarged outer portion 41x' enclosing a coiled expansion spring 43 and an outer device 41a' pivotally connected at its outer end to the outer end of the rocker 39. The device 41a' is provided with a head 41b slidably fitting the inner wall of the enlarged portion 41x' of the device 41a and a stem or shank 41b' which extends into and slidably fits the reduced portion 41x of the device 41a, the spring 43 being interposed between the head 41b and a cap 44 which is threaded on the outer end of the device 41a and through which the device 41a' slidably extends. In this arrangement, when current to the motor is cut-off, the crank 42 is in the position shown, but due to operation of the switch device in the casing 36, the motor 34 is operated to effect one rotation of its shaft and then stopped, so that the crank 42 swings upwardly and downwardly in making one revolution. In the upward movement of the crank 42 the power of the motor is transmitted through the device 41a, head 41b and device 41a' to the rocker 39 to move the rod 8 downwardly and in the downward movement of the crank 42, the power of the motor 34 is transmitted through the device 41a, the engagement of the spring 43 with the head 41b serving to insure movement of the rocker 39 therewith.

and raising of the rod 8. In this form the fuel is preferably delivered by a feed member such as shown in Figs. 2 and 3, operatively connected to a rocker 25x, which is controlled by a collar 16b fixed to a rod 18b'. The rod 18b' is slidably mounted in brackets 44, provided on the casing 1, the upper end of the rod 18b' being connected to the lower end of a link 18c, which is connected to and operated by the crank 42 of the motor 34, whereby feed of the fuel is controlled in co-ordinated relation to the operation of the rod 8. A magnetically operated brake (not shown) may be connected in series in the circuit for each motor 34, 34a, to insure stoppage thereof at the end of each rotation upon cut-off of the current in the circuit.

Fig. 5a illustrates a modified form of construction for feeding fuel from the chute 1c to the compartment 5. The upper side of the feed member 22x is concave and its opposite walls are concentric to the outer end wall of the offset 1b. The device 22x is fixed to a rock shaft 21x provided with a lever 45, the outer end of which is connected through a coiled spring 23x to an adjustable anchor 23a', the opposite end of the lever 45 being connected to the rocker 25', which is operated in the manner set forth in connection with the rocker 25' shown in Figs. 1 and 2. In this form of construction the feed member 22x is positively operated in one direction by the rocker 25' and in the opposite direction by the spring 23x which is strong enough to insure return movement of the member 22x to its normal position.

Provision is made for stopping the motor 31 at a predetermined position corresponding to that angular cut-off position of the valve elements 16b, 16b', wherein the steam supplied to the cylinders 12, 12x, has been exhausted and the pistons therein are in normal position. For this purpose I provide auxiliary cut-off means, indicated as entirely at 50 (Fig. 1), for controlling the motor 31, whereby it continues in operation, following the opening of the valve 32' in the manner already set forth. Of the auxiliary cut-off means 50, 50a indicates a separate circuit connected in the main circuit 32, in shunt relation to the switch 32' and supplying current to the motor and connected to suitable contacts in a switch box 50b, the circuit 50a across these contacts being normally closed by a spring operated movable contact 50b', which when operated breaks the circuit 50a. The contact 50b' is normally disposed in the path of movement of the throw provided on a cam 51, which is adjustably fixed in any desired manner to the shaft 16g, so that in each rotation of the latter the circuit is opened and closed. So long as the main circuit 32 is closed by the switch 32' and the motor 31 is operating to effect operation of the mechanism 9, the opening and closing of the separate circuit 50a in the manner above set forth will be ineffective, but following the operation of the switch 32' to open the main circuit 32, the motor 31 will continue to run until the cam 51 operates the contact 50b' and breaks the circuit 50a. From the foregoing description it will be observed that the auxiliary cut-off means 50 prevents stoppage of the mechanism 9 at a time when either piston in the cylinders 12, 12x, is at the upper end of its stroke or either valve 4, 4a, is in open position.

To those skilled in the art to which my invention relates many changes in construction and widely differing embodiments and applications

of the invention will suggest themselves without departing from the spirit and scope thereof. My disclosures and the description herein are purely illustrative and are not to be in any sense limiting.

What I claim is:

1. In apparatus of the class described, the combination with a gas producer, of an inverted casing the open end of which is related to the combustion chamber of said producer, spaced upper and lower annular walls carried by the side walls of said casing, valves fitting said walls and forming therewith upper and lower compartments, a chute for fuel, mechanism for feeding fuel from said chute to said upper compartment, valve operating members slidably mounted in the top wall of said casing for movement rectilinearly axially of said annular walls, one of said members consisting of a sleeve extending through said wall and connected to the valve for said upper compartment and the other member consisting of a rod slidably fitting said sleeve and extending therethrough and connected to the valve for said lower compartment, separate fluid operated means for operating said members in one direction, said fluid operated means consisting of a cylinder, a rod slidably extending therethrough and connected at its inner end to the adjacent valve operating member and provided with a piston reciprocable in said cylinder, an abutment carried by the outer end of said last mentioned rod and a spring interposed between said abutment and said cylinder for moving said rod to operate the adjacent member in the opposite direction, and means for supplying fluid to each of said cylinders to control the operation of said members in co-ordinated relation and relative to each other.
2. An apparatus as claimed in claim 1 wherein the fluid supply means includes a valve mechanism for supplying fluid to one cylinder and its exhaust therefrom during the period that the supply of the fluid to the other cylinder is cut off.
3. In apparatus of the class described, the combination of a casing related to a combustion chamber and having spaced upper and lower annular walls therein, valves fitting said walls and forming therewith upper and lower compartments, a chute for fuel, mechanism for feeding fuel from said chute to said upper compartment, a sleeve mounted in the top wall of said casing for movement rectilinearly axially of said annular walls and extending through said wall and connected to the valve for said upper compartment, a rod slidably fitting said sleeve and extending therethrough and connected to the valve for said lower compartment, mechanism for moving said sleeve and rod in one direction to move said valves into engagement with said annular walls, and fluid operated means for operating said sleeve and rod in the opposite direction in co-ordinated relation and relative to each other, said means including a valve mechanism for controlling the supply of fluid to said fluid operated means and exhaust of the fluid therefrom, said controlling means consisting of a motor, a source of electric current supply, main and separate circuits for said motor connected to electric supply source, means for opening and closing said main circuit and means controlled by said motor for opening said separate circuit in a predetermined position of said fluid operated means.
